Primary Examiner — George D. Kirschbaum*Assistant Examiner* — Sloan Rozin(74) *Attorney, Agent, or Firm* — Cantor Colburn LLP(57) **CLAIM**

The ornamental design for a digital signage, as shown and described.

DESCRIPTION

FIG. 1 is a perspective view of a digital signage showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a front perspective-explored view thereof;

FIG. 9 is a rear perspective-explored view thereof; and,

FIG. 10 is an enlarged view of the encircled portion 10 in FIG. 1.

The evenly dashed broken lines are for environmental purpose only and form no part of the claimed design.

In the drawings, the even-length broken lines depict portions of the digital signage that form no part of the claimed design.

1 Claim, 10 Drawing Sheets(56)
